APPARATUS FOR COOLING COMPRESSOR VALVES AND COMPRESSED FLUIDS

Application filed February 23, 1928. Serial No. 256,304.

Our invention relates to valves of that character adaptable for use in connection with compressors employed for compressing air or gases or in the manufacture of casing head gasoline; the principal objects of the invention being to prevent distortion of the discharge valve and adjacent parts of the compressor mechanism by heat transferred from the compressed fluid, to eliminate explosions, and to facilitate condensation of liquid components of the fluid.

In accomplishing such objects of our invention we have provided improved details of structure, the preferred forms of which are illustrated in the accompanying drawings, wherein:

Fig. 1 is a perspective view of apparatus for condensing gasoline vapors from natural gas originally delivered from a well or employed for compressing air or gas, including a compressor equipped for cooling in accordance with our invention.

Fig. 2 is an enlarged elevation of a compressor, partly in central vertical section, equipped with cooling apparatus embodying our invention.

Fig. 3 is a detail perspective sectional view of a discharge valve constructed in accordance with our invention.

Fig. 4 is a detail perspective view of the several elements of the discharge valve, shown in spaced but relative relation.

Referring more in detail to the drawings:

1 designates a compressor, including the cylinder 2 which may be supplied through an intake line 3 in accordance with common practice, and 4 a piston operable in the compressor chamber 5 and having a rod 6 operably connected with an engine 7 in accordance with common practice.

As the fluid delivered to the compressor is comparatively cool but is heated to high temperature as an incident of compression, our invention has no relation to the intake of such fluid to the compressor but is concerned only with the discharge of the fluid. Consequently, no reference will be made to the intake end of the compressor, but it is to be understood that in multiple stage compressors each stage is similarly supplied with cooling apparatus

as shown for the single stage compressor herein.

As the compressor is double-acting and the cooling mechanism duplicated at opposite ends of the piston chamber, but one mechanism will be described, with the understanding that such description relates equally to both.

Each of the heads 8 of the compressor is provided with a discharge port 9 opening to a valve chamber 10 preferably circular in cross section and communicating with a channel 11 constituting a manifold having outlet through a port 12 to a line 13 whereby fluid compressed by the piston and delivered to the valve is conducted to a suitable condenser presently described. The line 13 is preferably attached to the compressor housing by attachment of a plate 14, into which the line is threaded, to the housing by bolts 15.

Located within the valve chamber 10 is a discharge valve 16 of ordinary construction except for the improvements hereinafter specifically mentioned and comprising a housing 17 having open ports 18 in a restricted neck 19 terminating in a tubular throat 20, the body of the housing snugly fitting within the inner portion of the annular chamber 10.

Covering the housing 17 is a valve seat plate 22 provided with a plurality of segmental slots 23 through which the compressed fluid may be delivered from the compression chamber, the plate being shouldered to seat on the valve housing and center the plate in the housing.

24 designates a pin having a head 25 seated in a countersunk recess 26 in the top of the seating plate 22, a collar 27 extended through an annular aperture 28 in the plate 22, and a shank 29 extended below the plate 22 comprising a smooth portion 31 adjacent the collar 27 and a threaded portion 32 extending to the end of the pin. Located on the smooth portion 31 of the pin 25 is a valve stop plate 34 having segmental slots 35 corresponding to and adapted for registration with slots 23 in the valve seating plate 22, the plate 34 being shouldered on its under surface to reduce its mass and resultant heat retention.

The valve stop plate 34 is held against the

shoulder formed at the lower end of the collar 27 on pin 24, by a nut 36 and a bushing 37, both threaded onto the shank 29 of the pin; the bushing extending through the throat 20 of the valve housing and carrying a nut 38 which engages the end of the housing throat to bind the valve seating plate 22 to the housing through connection of the bushing with the pin 24.

10 The bushing 37 is abutted at its outer end by a bushing 40 threaded into a bottom plate 41 screwed to the compressor housing by bolts 42 to enclose the valve chamber, the discharge valve being therefore supported on the bushing 40 and removable as a body from the valve chamber when the bottom plate 41 is removed from the compressor housing.

15 Interposed between the valve seating plate 22 and the valve stop plate 34 is a valve disk 44 having a smooth central aperture 45 in which the smooth portion 27 of the shank 29 of the pin 24 is located, the valve disk 44 being of considerable less thickness than the length of the portion of the sleeve 27 of pin 24 remaining below the valve seating plate 22, so that the valve disk may move 20 vertically on the pin between the seating and stop plates. We provide the disk with apertures 46 and arrange the apertures to 25 avoid registration with the slots 23 of the valve seating plate but to register with the apertures 35 of the valve stop plate, so that when the valve disk is lifted during intake stroke of the compressor piston, it will be 30 pulled against the valve seating plate and seal the slots 23 to prevent back flow to the compressor through the discharge valve, and when the valve disk is at the other limit of its movement, the openings 46 will register 35 with the slots 35 in the valve stop plate and discharge the compressed fluid. In order to 40 maintain such relation of the valve disk to the plates 22 and 34 and of the plates relative to each other, we provide the seating plate 22 with a downwardly projecting pin 45 which extends through an aperture 48 in the valve disk into a socket 49 in the valve stop plate, thereby permitting vertical fluctuations of the valve disks without permitting 45 rotary movement of the valve disk relative to either of the plates or of the plates to each other. The valve disk 44 seats on a plurality of springs 50 retained in sockets 51 opening upwardly from the top face of the 50 valve stop plate 34, so that the valve disk 44 is always held up against the valve plates 22 during the intake stroke. Reduced ports 51' extend downwardly through the stop plate 34 from the sockets 51 so that a cooling liquid 55 may flow through said ports into the valve chamber when the valve disk is closed upon the sockets 51.

Up to this point we have, except for the ports 51', described only what is common in the construction of this type of discharge

valves, but will now proceed with a description of the adaptation of our improvement to such structure.

In accordance with our improvements, the bushing 40 is provided with a central longitudinal channel 52, terminating at its inner end in a flared mouth 53 and connected at its outer end with a supply pipe 54, through which cooling water or other liquid may be supplied under pressure. The flared mouth 75 53 of the channel in the bushing 40 registers with a corresponding mouth 55 of a channel 56 extending centrally through the bushing 37 and connecting with the central channel 57 extending through the pin 24 to near the head 80 of the pin. The channel 57 in the pin 24 has outlet through ports 58 that extend radially to the sleeve portion 27 of said pin into communication with radial channels 59 in the valve seating plate 22; the channels 59 having 85 outlet through downwardly opening ports 60 onto the top of the valve disk 44.

90 By this means water is admitted into the line of flow when the discharge valve is opened but is prevented from entering the compressor cylinder when the discharge valve is closed. We may also have the ports open through the apertures 46 of the valve disk 44.

95 The channel 57 in the pin 24 also has lateral outlet through radial ports 61 in the smooth portion 31 of the shank 29 of pin 24 into radial channels 62 in the valve stop plate 34, the channels 62 in turn having outlet to the vertically opening spring sockets 100 51 into the space below the valve disk 44. Consequently, when water or other cooling liquid is delivered under pressure from the pipe 54 through the bushings 40 and 37 into the interior of the pin 24, it is forced radially through the channels in the valve seating and stop plates into the valve chamber and onto opposite sides of the valve disk, thereby 105 cooling the valve body, the seating and stop plates, as well as the valve disk itself, to prevent distortion of the valve parts under extreme heat generated by compression of the fluid in the cylinder, the cooling fluid further 110 co-mingling with the compressed fluid to reduce its temperature and to prevent explosions and stimulate condensation of the fluid in the flow line, the condenser coil and the separating receptacle, and to eliminate 115 explosion hazards caused by ignition of combustible mixtures of air with gases or lubricating oil from the hot discharges from the compressor cylinder.

120 It is desirable to supply water in excess, that is, in quantity sufficient that it will cool the gases below the boiling point of the water and will wash the water and other condensable vapors from the air or gas.

125 The water or cooling fluid may be supplied to the compressor in the following manner and by the following instrumentalities:

The discharge line 13 for the compressed fluid leads to a condensing coil 63 which communicates with the separating receptacle 64 having a dome 65 from which is led a pipe 66 for carrying off non-condensable components of the compressed fluid. Leading from the receptacle at a relatively high elevation is a line 67 for conducting off the liquids of high specific gravity, such as gasoline, to a storage receptacle 68.

Opening from a relatively low level of the receptacle 64 is a pipe 69 for conducting water which, being immiscible and of lower gravity than the gasoline, has settled to the bottom of the receptacle, to a high pressure pump 70 connected by a line 71 with the supply pipe 54 leading to the discharge valve mechanism as presently described.

It will thus be seen that the water is cycled; the water vapor, almost always present in air or gas, being condensed to make up any losses and always providing a pure water that will not deposit mineral matter in the valve or in the pipe.

The line 71 is preferably connected with the supply pipe 54 through a four-way union 72, whereby the supply line is also connected with the discharge valve at the opposite end of the compressor by a branch 73, so that the other discharge valve may be cooled as described in connection with the valve heretofore mentioned. The fitting is also provided with a branch 74 opening into the discharge line 13 so that the cooling water may be commingled with the compressed fluid leaving the compressor manifold to cool the fluid as it leaves the compressor and thereby facilitate condensation and prevent overheating of the outlet line.

The high pressure pump may be operated through a transmission indicated by the gear wheels 75 and pulley 76 and belt 77 from the drive shaft 78 of the gas engine operating the compressor, thereby forming the entire apparatus into a compact unit entirely operable from a single source of power.

Assuming the parts to be constructed and assembled as described and the compressor, for illustration, connected with the gas relief line from a well being pumped by the air lift method, the operation is as follows:

The air, saturated with gasoline vapors, is admitted to the compressor and compressed in accordance with common practice. The compressed fluid heated to a high temperature by compression, is delivered through the discharge valve to the manifold chamber and out through the discharge line to the condenser. During passage of the fluid through the valve, water under high pressure is delivered through the valve bushings and center pin into the valve seating plate and the valve stop plate and jetted into contact with the valve disk, being distributed over the surface of the disk and forced out over the edge

of the disk into the valve chamber to cool the mechanical parts and being co-mingled with the compressed fluid to reduce temperature of the fluid. The compressed fluid passes on through the condenser into the separating receptacle where the gas and liquid separate, the gas being carried off for recirculation or other disposition, the gasoline or other high gravity liquid drained off from the upper outlet line, and the water pumped off from a lower outlet line for re-use in cooling the compressor and fluid discharged therefrom.

It is apparent that in accordance with our invention the cooling fluid is recirculated through the compressor and condenser in a closed circuit, thereby avoiding the scaling of pipes or conduits which would occur if fresh flow of mineral-containing water were employed.

While we have referred to compression of a specific kind of fluid, have illustrated a specific form of compressor and condenser, and have mentioned water as the cooling fluid employed, this has been merely to aid in explanation and without intent to limit scope of the invention.

What we claim and desire to secure by Letters Patent is:

1. In a discharge valve of the character described, a member having a channel opening through its exterior surface, and means for delivering a cooling fluid to said channel opening to be discharged over the exterior surface of said member.

2. In a discharge valve of the character described, a valve seating plate having radial channels opening through one of its faces to the exterior of the plate, and means for delivering cooling fluid to said channels to be discharged over the valve seating plate.

3. In a valve of the character described, the combination of a center pin having a longitudinal channel and lateral ports leading from the channel, a valve seating plate having radial channels communicating with the ports in said pin and opening through a face of the plate, and means for delivering a cooling fluid under pressure to the pin channel.

4. In a valve of the character described, the combination of a center pin having a longitudinal channel and lateral ports leading from said channel, a valve disk movable on the pin, a valve seating plate having radial channels communicating with the ports in said pin and opening through the face of said plate, and means for delivering a cooling fluid under pressure to the pin channel for discharge through the plate channels to contact with said disk.

5. In a valve of the character described, the combination of spaced valve seating and stop plates having channels opening through their facing sides, a valve cut-off plate movable between the seating and stop plates, and

means for delivering a cooling fluid to said channels under pressure for discharging into the valve cut-off plate.

6. In a valve of the character described, the combination of a center post having a longitudinal channel and two sets of lateral ports opening from said channel, spaced valve seating and stop plates fixed on said post having radial channels communicating with respective sets of ports in the post and opening through facing sides of the plates, a valve cut-off disk movable between the plates, and means for delivering cooling fluid under pressure to the channel in said post for delivering through the plates into contact with opposite faces of the valve cut-off disk.

7. In a valve of the character described, the combination of a center post having a longitudinal channel and two sets of lateral ports opening from said channel, spaced valve seating and stop plates fixed on said post having radial channels communicating with respective sets of ports in the post and opening through facing sides of the plates, the side openings in the stop plate constituting spring sockets, springs seated in said sockets, a valve cut-off disk seated on said springs and movable between the plates, and means for delivery cooling fluid under pressure to the channel in said post for delivering through the plates into contact with opposite faces of the valve cutoff disk.

In testimony whereof we affix our signatures.

IRWIN L. DUNN.
